UNITED STATES PATENT OFFICE.

LEONARDO CRIMAUDO, OF NEW YORK, N. Y.

FLYING-BOAT.

1,267,384.

Specification of Letters Patent. Patented May 26, 1918.

Application filed March 7, 1917. Serial No. 158,128.

To all whom it may concern:

Be it known that I, LEONARDO CRIMAUDO, a subject of the King of Italy, residing at New York, in the county of New York and State of New York, have invented new and useful Improvements in Flying-Boats, of which the following is a specification.

This invention has to do with flying boats, and the principal objects thereof are: first, to produce a device of this character, provided with elements arranged in such manner as to adapt it for travel on the land, in the water and through the air; and, second, to provide such a device with a main steering mechanism common to the mechanisms by which the device is guided or steered on the land, in the water and through the air.

Another object is the provision of a device of this character having hinged wings or planes which are designed to be reciprocated or flapped in vertical arcs in unison for sustaining flight through the air, and which may be brought to rest when the boat is to travel on the land or in the sea.

With the foregoing and other objects, which will become apparent as the description progresses, the invention consists in the novel construction, combination and arrangement of parts hereinafter described and shown in the accompanying drawings, forming a material part of this specification, and in which:

Figure 1 is a view in side elevation of the device, the operating mechanism being shown in dotted outline, and the rudder mechanism being partly broken away.

Fig. 2 is a longitudinal sectional view, taken on the line 2—2 of Fig. 1.

Fig. 3 is a similar view, taken on the line 3—3 of Fig. 1.

Fig. 4 is a cross sectional view, taken on the line 4—4 of Fig. 1.

Fig. 5 is a similar view, taken on the line 5—5 of Fig. 1.

Fig. 6 is a rear elevational view.

Fig. 7 is an elevational view of the main steering mechanism, showing the same set in position for steering the device on land.

Fig. 8 is a similar view, but showing the mechanism set in position for steering in the water and through the air.

Fig. 9 is a view in side elevation of the eccentric means for flapping the wings, and

Fig. 10 is a detail fragmental view of

the steering column illustrating the ball and socket joint connection.

In describing the invention in detail reference will first be had to Fig. 1, wherein the numeral 15 represents the hull of the boat which is provided throughout its length with a longitudinal partition or flooring 16, upon which is located in the forward end a motor 17, and in the stern motor 18, and adjacent the center therebetween a series of batteries 20 representing a source of power for the motors and connected therewith with the usual electric wiring connections.

21 represents the seat for the pilot who is protected from the elements by the wind shields 22. Secured exteriorly of the bow of the boat on the main drive shaft 23 is an air propeller 24, which serves to propel or drive the boat through the air, and also on the land. Secured exteriorly of the stern of the boat on the drive shaft 25, driven by the motor 18, is a water propeller 26 to drive the boat through the water.

Exteriorly hinged to the stern of the boat by the hinges 27 and 27' is a vertical rudder 28, which is designed to guide or steer it when traveling in the water and through the air. To enable it to travel on land, the boat is provided with a running gear which is secured to the underside of the hull, a part adjacent the bow, and a part adjacent the stern.

The forward running gear consists of the supporting frame 29, in the rear element of which is journaled an inflated wheel 30, and in the forward element of which is swiveled a shaft 32, having a lower bifurcated end in which is journaled a similar wheel 31. The rear running gear consists of the frame 33 carrying an axle 34, to which are attached the wheels 35, similar to those carried by the forward running gear.

As best shown in Figs. 7 and 8, the upper end of the shaft 32 is journaled in bearing 36 and in angular bracket 37, both secured to the inner side of the hull. Fast on shaft 32 between the bearings 36 and 37 is a rocker arm 38, the free end of which is provided with a toothed gearing-head 38'. Also secured to the inner bottom of the hull is a longitudinal bracket 39 having its opposed ends formed with upwardly projecting shoulders or bearings 40 and 40'. Revolute in the bearing 40' and held vertically

in position by the bracket 41, on the vertical support 42, is a steering column 43 carrying at its top end a hand wheel 44, positioned immediately in front of the pilot's seat 21 for convenient manipulation by the pilot. In order to compensate for the angle it is required to make, the steering column 43 is made in two parts operatively coupled by means of the ball and socket joint 44 provided just above the bracket 41. The vertical portion of the steering column is provided with a longitudinal lug 45 adapted to fit in a groove provided in the hub of the gear 46, and which is adapted to mesh 15 with the grooved head 38' when at its lowest elevation.

Revolutionally mounted at its lower end in the bearing 40 and at its upper end in the bearing 47' provided in the end of the angular bracket 48 is a vertical shaft 49 on which is rigidly secured the bevel gear 50. Also fast on 20 49, immediately below said bevel gear is a rocker arm 51 which is formed with a toothed head 51', similar to the head formed with the arm 38, designed to mesh with the gear 46 when in elevated position.

To provide for the shifting of gear 46, I employ a lever 52 which is pivoted at one end as at 53 to a bracket 54, and at the other 30 end to a sleeve formed on the underside of said gear 46. Positioned within convenient reach of the pilot, and provided with a shank of bell-crank formation, pivoted at 55, is an operating lever 56. The lower end of this 35 lever is pivotally connected with the forward portion of 52 by a link 57.

Journaled in the bearing 58 provided in the bracket 48 is a longitudinal shaft 59 which carries a bevel gear 60 in mesh with the bevel gear 50. As shown in Fig. 1, this shaft 59 extends to the stern of the boat and is supported in the bearings provided in brackets 61 and 62, the latter bracket being angular in form and having at its free end a bearing 63 wherein is journaled the lower end of the vertical shaft 64, the upper end of which is journaled in the bracket 65, and provided with a gear 66 (Fig. 2). A pair of bevel gears 67 and 68 provide for the transmission 45 50 of motion from shaft 59 to shaft 64. As best shown in Fig. 2, a transmission arm 69 having a gearing-head in mesh with the gear 66 serves to transmit motion to the rudder 28.

From the foregoing it will be obvious that 55 when the gear 46 is in mesh with the rocker arm 38, each movement of the steering column 43 will produce a similar turn of wheel 31. Also it will be obvious that when the adjustable gear 46 is raised so as to mesh 60 with the head of the transmission arm 51, each movement of the steering column will be transmitted to the rudder 28.

In Fig. 1, it will be seen that the longitudinal shaft 70, journaled in the bearings as 65 71 on the under-side of the flooring 16, is

driven by the main shaft 23 through the engaged gears 72 and 73. As shown in Fig. 5, the shaft 70 carries a gear 70' to drive the large gear 74 which has formed on its face an eccentric groove 75. A horizontal arm 70 76 is centrally secured to a pin 77 the opposite end of which is provided with a roller 78 (Fig. 9) operative in the eccentric groove 75. Hinged in the oppositely disposed brackets 79 and 79' on the exterior of the hull are wings or planes 80 and 80', which are provided with arms 81 and 81' angularly projecting therefrom and extending into the hull. Pivots connecting the free ends of arms 81 and 81' with the free ends of the horizontal lever 76 are links 82 and 82'. By means of this arrangement, the lever 76 is given a vertical motion in the same plane when the shaft 70 is rotatated, by which motion the wings 80 and 80' are reciprocated or 85 flapped in vertical arcs once with each rotation of the shaft. In order to make the flapping movements of the wings positively uniform, a spring 83 is employed to connect the pivoted ends of the arms 81 and 81'. 90

A second pair of wings 84 and 84' are similarly secured near the bow of the boat. These are operated by identical mechanism driven by the shaft 70. In this manner I provide for the flapping in unison of the two 95 pairs of wings.

Having thus described my invention, what I claim as new and desire to secure by Letters Patent is:—

1. In a device of the character described, 100 the combination with a hull carrying a running gear including a swiveled wheel, an air propeller carried on the bow of the boat and means for driving it, a water propeller carried on the stern of the boat and independent means for driving it, a rudder carried by the stern of the boat adapted to direct its course either in the air or in the water, wings hinged exteriorly of the hull of the boat and adapted to flap in unison in 105 pairs in vertical arcs, means for operating the wings from the air propeller driving mechanism and a main steering mechanism common to the running gear and to the rudder steering mechanism for operating each 110 of them independently.

2. In a device of the character described, the combination of a hull provided with a running gear one element of which is a swiveled wheel, an air propeller carried by 120 the bow of the hull, means for driving the propeller, a water propeller carried by the stern of the hull, independent means for driving the same, a vertical rudder carried by the stern of the hull, wings hinged exteriorly of the hull and adapted to flap in unison in vertical arcs, said wings being arranged in pairs, a main steering mechanism 125 adapted to be manipulated to control independently the movements of either the swiv- 130

eled wheel or the rudder, and means for operating the wings from the air propeller driving mechanism.

3. In a device of the character described, 5 in combination with a hull having a running gear including a swiveled wheel, a water propeller carried by the stern, a rudder carried by the stern adapted to direct the course of the boat in the water and in 10 the air, and a steering mechanism capable of adjustment to control independently the movements of either the swiveled wheel or the rudder.

4. In a mechanism for flying craft, a steering column one portion of which is vertical, 15 a gear wheel slideable on the vertical portion and rotatable therewith, a vertical shaft, a ground wheel carried thereby, a rocker arm having a toothed gearing-head associated 20 with the shaft, an arm pivoted at one end to a fixed support and at the other end to the gear wheel, and means connected with said arm for shifting said gear wheel into and out of mesh with the gearing-head of 25 said rocker.

5. In a mechanism for flying craft, a steering column having a lower vertical element, 30 a gear wheel slideable on said vertical element and rotatable therewith, a vertical shaft provided with a ground wheel, a rocker arm fast on said shaft having a toothed gearing-head on its free end, a second vertical shaft, a similar rocker arm fast thereon but higher in elevation, an operating lever 35 and means connecting the operating lever with the gear wheel by which to shift the

latter into or out of mesh with either of the toothed gearing-heads of said rocker arms.

6. In a mechanism for flying craft, a steering column provided with a wheel handle 40 and having a lower vertical element, two shafts secured for rotation parallel to said vertical element but spaced therefrom, a rocker arm fast on each shaft and each provided on its free end with a toothed gearing- 45 head, a gear wheel rotatable with and axially movable on the vertical element, and means for moving said gear wheel so as to mesh when in one position with the gearing-head of one rocker arm and when in another position with the gearing-head of the other rocker arm. 50

7. In a mechanism for flying craft provided with running gear and rudder mechanisms, a steering column having a vertical 55 element, a gear wheel rotatable with and axially movable on the vertical element, a pair of shafts parallel to said vertical element but spaced therefrom, a rocker arm carried by each shaft and each provided 60 with a toothed gearing-head, said arms being arranged in different horizontal planes, means for shifting the gear wheel into and out of engagement with each of the toothed gearing-heads, means carried by one vertical 65 shaft for controlling the direction of movement of the running gear and means operable by the other vertical shaft for controlling the rudder mechanism.

In testimony whereof I have signed my 70 name to this specification.

LEONARDO CRIMAUDO.
